ACCOUNTING MACHINE

Edward J. Rabenda, Binghamton, N. Y., assignor to International Business Machines Corporation, New York, N. Y., a corporation of New York

Application July 16, 1938, Serial No. 219,558

10 Claims. (Cl. 235—61.8)

This invention relates to accounting machines and more particularly to accumulating mechanisms employed therein. In the construction of an accumulating mechanism there is usually provided for each denominational order thereof combined adding and subtracting mechanism which is controlled by one pair of magnets to enter an amount additively and by another separate pair of magnets to enter an amount subtractively.

It is an object of the present invention to simplify the mechanism required for a denominational order of an accumulator by providing a single pair of magnets for controlling both adding and subtracting operations.

It is a further object of the invention to simplify the controlling circuit connections required for the operation of the accumulating mechanism of a tabulating machine.

Further objects of the instant invention reside in any novel feature of construction or operation or novel combination of parts present in the embodiment of the invention described and shown in the accompanying drawings.

In the drawings:

Fig. 1 is a view showing one denominational order of an accumulator.

Fig. 2 is a view similar to Fig. 1 with certain of the parts removed and others moved to operated position.

Fig. 3 is a diagrammatic representation of the operating connections of a tabulating machine showing the relationship between the accumulator and the printing mechanism.

Fig. 4 diagrammatically represents the card feeding and analyzing mechanism of a tabulating machine.

Fig. 5 is a detail of the total readout and tens carry mechanism.

Fig. 6 is a vertical section taken substantially along lines 6—6 of Fig. 2.

Fig. 7 is a similar view with the parts shown in outside view.

Fig. 8 is a wiring diagram of the electrical circuits of a simplified tabulating machine.

Fig. 9 is a timing diagram of the circuit closing devices shown in Fig. 8.

Fig. 10 is a portion of a perforated record card.

Fig. 11 is a portion of the circuit diagram of Fig. 8 showing a different plug connection.

Referring to Figs. 3 and 4 there is represented the essential elements of a well known Hollerith tabulating machine such as shown in the Patent No. 2,042,324 granted May 26, 1936 to J. R.

Peirce. A main driving shaft 10 through gearing designated 11 drives a shaft 12. In Fig. 4, shaft 12 through suitable gearing drives pairs of card feed rollers 13 and a picker knife 14 to advance record cards 15 singly from a supply hopper to pass a set of upper analyzing brushes designated UB and a set of lower analyzing brushes designated LB. The relationship of the brushes is such that as a card passes the lower brushes the next following card passes the upper brushes so that the correspondingly numbered index point positions of the two cards are concurrently sensed.

In the path of the cards there are provided the usual card levers designated LCL and UCL which serve to close their related contacts 16 and 17 respectively, when cards are traversing the brushes. The shaft 12 makes one complete revolution for each card advanced to pass the brushes.

In Fig. 3 shaft 12 is shown as carrying a pair of complementary cams 18 which through follower 19 and linkage designated 20 causes oscillation of shaft 21. Arm 22 carried by the shaft 25 has link connection 23 with a bail 24 pivoted at 25. At 25 there is also pivoted an arm 26 whose left hand end is connected by a link 27 to type bar 28 which is suitably mounted for vertical reciprocation. The type bar carries the usual type 30 elements 29 which, through the connections traced, are advanced to pass a printing position opposite platen 30 as the corresponding index point positions of the record cards pass the sensing brushes LB. As the type bar moves upwardly, it may be interrupted, to select any element 29, by printing magnet 31, the attraction of whose armature will rock latch 32 to release stopping pawl 33 for engagement with one of the teeth 34 in the type bar 28. After all the 40 type bars have been positioned, the usual printing hammer 35 is tripped to take an impression therefrom.

The main drive shaft 10, through gearing 36, drives a vertical shaft 37 which has the usual beveled gear connection 38 with transverse shafts 39. The ratio of the gearing is such that shaft 39 makes one revolution for each card advanced through the sensing mechanism. For each denominational order of the accumulating mechanism, there is provided on each shaft 39 a gear 40 each of which serves to drive a denominational order unit of the accumulating mechanism. For the illustration of the present invention, the entire mechanism of the tabulating machine to which it is applied is not set forth in detail and

reference may be had to Patent 2,042,324, hereinabove referred to, for further structural details. It may be noted that in the machine of the patent the card feeding mechanism and the printing mechanism are disengageable from the constantly running drive shaft 12 (corresponding to shaft 17 of the patent) through clutch devices, and that so-called group control mechanism is included in the machine. These features are not repeated herein in order to simplify the disclosure. Suffice it to say that the group control mechanism serves to stop the card feed upon change in group number of successive cards, or by means of a stop key such interruption may also be brought about. When the card feed comes to rest under such circumstances, it will be in the so-called "home" position with the next card to be fed holding the card lever contacts 16 closed.

Referring to Figs. 2 and 6, meshing with each gear 46 is a gear 41 carried by a member 42 which is mounted for rotation, through suitable roller bearings, on a post 43 secured to a plate 44. The gear 41 is thus in constant rotation as long as the main drive shaft 10 operates. The member 42 carries a number of pins 45 which project through the cooperating notches in a disk 46 which is carried by the member 42 but free to move thereon in an axial direction and constrained to rotate therewith through the pins 45. Extending through the member 42 is a stud 47, one end of which carries a toothed wheel 48 and the other end carries a structure generally designated 49 upon which is mounted a pair of electrically connected brushes 50 (see Fig. 5) which cooperate with segments 51 and a common arcuate conductor 52. The toothed wheel 48 constitutes the adding or accumulating element and is provided with teeth 53 facing the disk 46. The latter is also provided with teeth 54 as shown in Figs. 6 and 7.

Lying between the disk 46 and wheel 48 is a coil spring 55 which serves to hold the parts in the position shown in Fig. 6. The wheel 48 is normally locked in position by a detenting finger 56 (see Fig. 1) which is carried by a member 57 pivoted on stud 58. The member 57 is provided at its upper end with a beveled disk 59 which normally occupies a position adjacent to disk 46 as shown in Fig. 6, Fig. 7. The member 57 is urged to rotate in a counterclockwise direction by a spring 109 but is normally restrained against such rotation by the engagement of armature 61 with the arm 62 of member 57. Upon energization of magnet 63, armature 61 will be attracted to release arm 62 whereupon spring 109 will rotate member 57 so that disk 59 will move to engage disk 46 and rock its teeth 54 into engagement with the teeth of wheel 48. At the same time rocking of member 57 will remove detent 56 out of engagement with wheel 48 so the latter is thus free for rotation with the constantly rotating disk 46. This type of clutching mechanism is the same as shown and described in Patent 2,165,288, granted July 11, 1939, to A. W. Mills, which patent may be referred to for further detailed explanation.

Magnet 63 is energized in response to the sensing of perforations in the record cards as they traverse the sensing brushes LB. The controlling circuits will be traced hereinafter in connection with the circuit diagram. The amount that wheel 48 is advanced depends on the time at which the magnet is energized with respect to the time at which member 57 is positively re-

stored to its initial position. This restoration is effected by a roller 64 carried by gear 41 which, as the gear rotates, engages an extension 65 on member 57 to positively rock the member in a clockwise direction causing it to be relatched by the armature 61.

This relatching takes place at a definite time in the cycle and if the initial tripping is in response to the sensing of, let us say, a 6 hole in 10 a card column the clutching engagement between disk 46 and wheel 48 will occur 6 steps before knock-out is effected. When the member 57 is restored, the detent finger 56 engages the wheel 48 to positively lock it against further advance 15 and disk 46 will be disengaged from the wheel. Secured to wheel 48 is the usual tens carry disk 66 with which a follower 67 cooperates. When the disk is positioned to represent a 9, follower 67 is permitted to rock slightly counterclockwise and through a pin 68 will enable brush 69 to contact a conducting element 71 (see Fig. 5).

When the disk 66 passes through zero position, follower 67 is rocked clockwise to cause brush 69 to contact with a conducting element 70. Latch 25 72 is provided to hold the follower 67 in its rocked position until released by a roller 73 carried by the gear 41. The brush 69 and elements 20 70, 71 control tens carry circuits for energization of appropriate magnets 63 and where a carry 25 operation is to be effected into any order the magnet 63 in that order is energized after the roller 64 has restored member 57 and one step later, after the energization of the magnet for carrying has taken place, a second roller 74 again 30 disengages the clutch after the wheel has advanced an additional step.

The magnet 63 is provided with a second armature 75 whose free end engages the right-hand end of a lever 76 pivoted at 77. The lever 76 is normally engaged by a latch 78 which is connected by a link 79 to an arm 80 pivoted at 81 and whose free end cooperates with a cam 82. The cam 82 is secured to gear 41 and rotates therewith. During the entering portion of the cycle, follower 80 rides on the low portion of the cam so that the latch 78 is in a position as shown in Fig. 1, during additive entering operations, and although energization of magnet 63 will attract both its armatures 61 and 75, the latter will move idly.

The operation of the mechanism for adding as described hereinabove is substantially in accordance with the manner in which adding has been effected in prior machines. That is, the adding clutch is tripped at a differential time in response to the sensing of a perforation in a card column and declutching is positively effected at a definite time in the cycle. Before explaining the operation of subtraction, the controlling circuits for adding operations will be explained in connection with the circuit diagram.

Referring to Fig. 8, 83 represents a line leading to one side of a source of current and 84 represents the opposite line. Upon closure of switch 85 a circuit is completed through motor M which serves to drive the main shaft 10 of the machine from which the card feeding, printing, and accumulating mechanism are driven in synchronism. As a preliminary, plug connections 86 are made from the lower brushes LB to plug sockets 87 as indicated and a further plug connection 86a is made between sockets 88 and 89. The connection 92 between sockets 91 and 93 is also made when adding operations are to be effected. As the card advances through the sensing unit, it

will engage the lower card lever LCL to close contacts 16 thereby completing the circuit from line 83, contacts 16, relay magnet R1, to line 84. Relay R1 closes its contacts R1a to provide a holding circuit through cam contacts C11. The contacts C11 and 16 serve to keep relay R1 energized as long as cards continue to pass the lower brushes in succession. Upon closure of contacts 16 a further circuit is traceable from line 83, through contacts 16, wire 90, contacts R5b, R6b, contacts C12, to plug socket 88, thence through connection 86a to socket 89, contacts R2b, socket 91, connection 92, to socket 93, cam contacts C13, relay magnet R3 and thence to line 84.

Contacts C13 are timed as shown in Fig. 9 to close during the adding portion of the cycle so that during such period the relay R3 is energized to close contacts R3a whereby the plug sockets 87 are connected to wires 94 extending to the accumulator magnets 63. If the card now traverses the lower brushes, circuits through the magnets 63 will be completed. An adding circuit may be traced from line 83 through cam contacts C14, contacts R1b (now closed), to the lower brush contact roller and thence through the perforation in the record card, lower brush LB, connection 86, socket 87, contacts R3a, wire 94, magnet 63 to line 84. The accumulator wheel will thereupon be engaged for rotation with the driving element of the clutch, and at the knock-out time disengagement will be effected.

At the carry time, cam contacts C10 close, completing a circuit from line 83, through wire 95, contacts R1c (now closed), contacts C10, wire 96, to the contact elements 70. At the same time a pair of contacts C22 close, completing a circuit from line 84, contacts R1d, contacts C22, relay magnet R4 to line 83. Relay R4 closes its contacts R4a so that for any accumulating wheel that has passed through 10, a circuit from wire 96 will continue through contact element 70 in the unit order for example, the units brush 69 to relay contacts R4a in the tens order and thence through the wire 94 to the tens order magnet 63. If the tens order wheel stands at 9, the circuit will branch to contact element 71 in the tens order, brush 69 and through contacts R4a in the hundreds order to the magnet 63 in that order. The brush 69 in the highest order of the accumulator is connected by wire 97 to the contacts R4a in the units order. This connection is for the purpose of subtraction as will be explained.

Subtraction

When subtracting operations are involved, a plug connection 100 is made from the socket of a predetermined brush UB to a plug socket 101. The brush socket selection is that of the brush which traverses the column of a record card in which a perforation is made in the "11" or "X" index point position indicating that the amount contained on that card is to be subtractively entered into the accumulator. A further plug connection 102 is also made between a plug socket 103 and the plug socket 104.

Assuming now that a record card containing a perforation in the X position passes the sensing brushes, as this card traverses the upper brushes a circuit will be completed when the X hole is sensed which is traceable from line 83 through cam contacts C18, upper card lever contacts 17 (now closed) the appropriate brush UB, connection 100, socket 101, cam contacts C16, relay magnet R2, to line 84. Relay R2 closes its contacts R2c which provide a holding circuit traceable

from line 84 through relay R2, contacts R2c, contacts C17, line 83. Contacts C17 are timed to maintain the relay magnet energized throughout the entering portion of the next succeeding cycle, during which the record card traverses the lower brushes LB.

With relay R2 energized, its contacts R2a are closed so that the entering circuits traced above from line 83 to socket 89 will continue through contacts R2a, socket 103, connection 102, socket 104, relay R3, to line 84. This effects closure of contacts R3a, which will remain closed throughout the entering portion of the next cycle. Before the record card engages the lower brushes, cam contacts C15 close at the time indicated in Fig. 9 to complete a circuit from line 83 through contacts C15 to the contact roller of the lower brushes. At this time, there is no card insulating the brushes from the contact roller so that a circuit will continue through all the brushes LB, all the plug connections 86, through sockets 87, contacts R3a and the adding magnets 63, to line 84.

The relative positions of the various parts of the mechanism, at this time, are shown in Fig. 2 and their functioning can best be explained at this time with particular reference to the timing diagram of Fig. 9. The cam 82 holds arm 80 toward the left to rock latch 78 out of engagement with the lever 76. The lever, however, is held in position by engagement of its left-hand end by roller 105. Energization of magnet 63 has attracted both its armatures 61 and 75. The former has released member 57 and the member has rocked slightly in a counterclockwise direction but not sufficiently to effect clutching engagement.

Full rocking of the member 57 is prevented by engagement of its extension 65 with an arcuate shoe 106 carried by the gear 41. The shoe 106 will delay the clutching engagement until the beginning of the next following cycle, just before the 9 index point position is sensed by the lower brushes. Rocking of member 57 has caused a pin 107 to release a spring pressed latch 108 for engagement with link 79 so that, as cam 82 continues to rotate, the follower 80 will be held in the position shown in Fig. 2. In other words, when the "X" perforation is sensed by the upper brushes the plug connected magnets 63 are energized to trip their clutches but actual clutching engagement is delayed until the beginning of the next cycle.

When extension 65 rides off shoe 106, complete clutching action is effected and all the accumulator wheels will commence to turn at the 9 time in the cycle to begin entering nines in each order. In the meantime, when roller 105 leaves the left end of lever 76 the magnet 63 will have become deenergized so that its armature 75 is back in latching position with respect to lever 76.

As the card now traverses the lower brushes, circuits will be completed upon the sensing of perforations which are traceable through the magnets 63 through the same circuits as traced hereinabove for adding operations. Energization of magnet 63 at this time, however, will cause its armature 75 to release lever 76 whereupon the spring 109 will rock the lever in a counterclockwise direction and a pin 110 therein will engage arm 62 to rock member 57 clockwise and effect declutching of the accumulator wheel, after the wheel has advanced an amount representing the nines complementary value of the number represented on the card. Restoration of member

57 will disengage latch 108 from link 79 so that cam 80 will again rock into engagement with its cam 82.

Briefly summarizing the mechanical operation involved in entering complements the sensing of an X hole causes energization of magnet 63 to effect a slight rocking of member 57 and cam 82 through lever 80 and the link 79 causes disengagement of latch 78 to free lever 76, so that at the end of the cycle the lever 76 is restrained against counterclockwise rotation solely by the armature 75. At the beginning of the next cycle actual clutching engagement is effected when member 57 rides off shoe 106 to begin adding nines into all orders and the engaged clutches will thereafter be uncoupled at differential times when the magnets 63 are energized through the same circuit connections as when adding, the energization at this time causing release of lever 76 so it may in turn rock member 57 clockwise.

Total printing

Referring to Fig. 8, the brushes 50 integral with the accumulating wheel take differential positions in accordance with the amount standing on the wheel, to connect the segments 51 with the common conductors 52. When it is desired to print the amount standing on the accumulator, key contacts 120 are closed to complete a circuit from line 84 through contacts C21, relay magnet R5 to line 83. Relay R5 closes its contacts R5a to provide a holding circuit through contacts C19. Relay R5 also closes its contacts R5c connecting the print magnets 31 to the related common conductors 52. A plurality of impulse emitting cam controlled contacts designated C0 to C9 are timed to connect the 9, 8, 7, etc. segments 51 in turn to line 83 through normally closed relay contacts R6e so that, for example, with the brush 50 of the units order standing at "6" as indicated in dotted lines, a circuit is traceable from line 83, through cam contacts C6, contacts R6e, 6 segment 51, brush 50, units conductor 52, contacts R5c, print magnet 31, to line 84. In this manner the amount standing on the accumulator may be printed. Relay R5 also opens a pair of contacts R5b to prevent energization of relay R3 during a total printing cycle.

Resetting

Resetting is effected by entering into the accumulator the tens complement of the amount standing therein and is brought about as follows: Closure of the reset key contacts 122 will complete a circuit from line 84, contacts C21, 122, relay magnet R6, to line 83. The relay will close its contacts R6a to provide a holding circuit through cam contacts C20. The relay will also close contacts R6c to connect the readout strips 52 to wires 94, leading to the accumulator magnets 63. The relay R6 also causes opening of its contacts R6f and closure of contacts R6i, the effect of this shifting of the latter contacts is to connect the cam contacts C9, C8, etc. to the segments 51 in reverse order. That is, the contacts C9 will be connected to the zero segments 51, the contacts C8 to the 1 segments 51, etc. Thus, for example, with the brush 50 of the units order standing at 6 as indicated, a circuit will be traceable when cam contacts C3 close, from line 83, contacts C3, 70 contacts R6f, 6 segment 51 in the units order, brush 50, conductor 52, contacts R6c, wire 94 to magnet 63 tripping the latter at the 3 time to enter a 3 in that order.

Relay magnet R6 also closes a pair of contacts 75

R6d to enter an additional elusive one into the units order to raise the "9" standing therein, after the contacts C9 to C0 have operated, to zero. This circuit is traceable from line 83 through wire 95, contacts R1c, cam contacts C10 (which close at the carry time), contacts R6d, wire 94 to magnet 63 of the units order and thence to line 84. With this and the other orders standing at 9, the entered unit will be transmitted through the carry contacts 69, 71 to each of the higher orders and advance them to zero. Relay R6 also opens a pair of contacts R6b to prevent energization of relay R3 during the resetting operation.

In certain classes of work, it may be desirable to have all cards which pass through the machine, effect subtractive entry of the amounts recorded thereon, irrespective of whether there is a special "X" hole or not. In such case, a plug connection 130 is made as shown in Fig. 11 between sockets 88 and 104, so that for each card, relay R3 will be energized while contacts C12 are closed, and contacts C15 which close during such time will energize magnets 63 to control the entry of nines and later, the circuits through the brushes LB will again energize the magnets 63 to interrupt advance of the accumulator wheels when the nine complement has been entered.

Likewise, if only adding is to be effected a single connection may be made between sockets 30 88 and 93 instead of the two connections 86a and 92 shown in Fig. 8.

While there has been shown and described and pointed out the fundamental novel features of the invention as applied to a single modification 35 it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In an accumulating unit for an accounting machine, an accumulating wheel which is to be advanced to any of a plurality of rotative positions to represent different amounts, a continuously rotating driving element, said wheel and driving element being adapted for clutching engagement with each other during a cycle of rotation of said driving element, a magnet, a pair of separate armatures operated thereby, a clutch engaging device normally held by one of said armatures to cause, upon release, clutching engagement between the wheel and driving element, means operative during a predetermined period in the rotation of the driving element for preventing clutching engagement when said clutch engaging device is released upon a first energization of said magnet during said period and enabling clutching engagement at the end of said period, a releasing member normally held by the other of said armatures to cause, upon release, restoration of said clutch engaging device, a latch normally holding said releasing member against operation, means operative during said predetermined period for moving said latch out of engagement with said releasing member and means controlled by said clutch engaging device, when released during said predetermined period, for locking said latch in ineffective position whereby said other armature may subsequently effectively release said releasing member upon a second energization of said magnet to cause disengagement of said wheel and driving element.

2. In an accumulating unit for an accounting machine, an accumulating wheel which is to be advanced to any of a plurality of rotative positions to represent different amounts, a continuously rotating driving element, said wheel and element being adapted for clutching engagement with one another during a cycle of rotation of said driving element, devices for coupling said wheel to said element for rotation therewith, devices operating upon said coupling devices to effect uncoupling, a single magnet for controlling the operation of both said devices, circuit connections including said magnet for energizing the same during a cycle of operation of said driving element, said coupling devices being responsive to one energization of said magnet, means for causing said second named devices to be unresponsive to said energization, and means controlled by said coupling devices and said driving element for rendering said causing means ineffective so as to enable said second named devices to be responsive to a second energization of said magnet during said cycle of operation.

3. In a machine of the class described, an accumulating wheel which is to be advanced to any of a plurality of rotative positions to represent different digits, a continuously rotating driving wheel, said wheels being adapted for clutching engagement with each other during a cycle of rotation of the driving wheel, a spring urged coupling device, a latch for holding said device in ineffective position, a magnet having a pair of independent armatures, one of said armatures constituting said latch, a knockout lever for said coupling device, a latch normally holding said lever in ineffective position, the second armature also restraining the lever against movement, means for energizing said magnet to effect release of said coupling device at a predetermined point in a cycle of rotation of said driving element, a member movable with said driving element for delaying effective coupling action until a predetermined point in the following cycle, further means movable with said driving element for releasing said lever latch when the coupling device is initially released, means for holding said lever latch in released position whereby the lever is held solely by the second armature, and means for energizing said magnet during said following cycle to cause the second armature to release said lever whereby said coupling device will be operated to effect uncoupling of the wheels.

4. In a machine controlled by record cards containing perforations differentially located therein, a pair of spaced sensing elements, means for feeding a record card to pass said elements in succession, a single magnet having a single winding, a circuit connection thereto, means for connecting said circuit connection to the second of said sensing elements, means controlled by the first of said sensing elements upon sensing a perforation in a predetermined position of the card for effecting an operation of said connecting means and for maintaining the same in operation, means including said second sensing element for completing a circuit to energize said magnet through its circuit connection and said connecting means before the leading edge of the card has passed the second element and after the leading edge has passed the first sensing element, means also including said second sensing element effective upon sensing a perforation as the card passes said second element for com-

pleting a second circuit to energize said magnet a second time through said circuit connection and connecting means, an accumulating wheel, a driving element, said wheel and element being adapted for clutching engagement with one another, devices for coupling the two, devices operating upon said coupling devices to effect uncoupling, said coupling devices being responsive to said magnet when it receives said first impulse, means for causing said second named devices to be unresponsive to said first energization and means controlled by said coupling devices and said driving element for rendering said causing means ineffective so as to enable said second named devices to be responsive to a second energization of said magnet whereby the wheel and element are uncoupled.

5. In a machine controlled by record cards containing perforations differentially located therein, a sensing element, means for feeding a record card to and by said element, a magnet, a circuit connection thereto, means for connecting said circuit connection to said sensing element, means for effecting an operation of said connecting means, means for rendering the effecting means continuously effective, means for completing a circuit to energize said magnet through its circuit connection, said sensing element, and said connecting means as the card advances to and before the card passes the sensing element, means rendered effective by said sensing element upon sensing a perforation as the card passes said element for completing a second circuit to energize said magnet a second time through said circuit connection and said connecting means, an accumulating wheel, a driving element, said wheel and element being adapted for clutching engagement with one another, devices for coupling the two, devices operating upon said coupling devices to effect uncoupling, said coupling devices being responsive to said magnet when it receives said first impulse, means for causing said second named devices to be unresponsive to said first energization and means controlled by said coupling devices and said driving element for rendering said causing means ineffective so as to enable said second named devices to be responsive to a second energization of said magnet whereby the wheel and element are uncoupled.

6. In a machine controlled by records containing perforations differentially located thereon, a sensing element, means for feeding a record card to and by said element, a magnet, a circuit connection thereto, means for connecting said circuit connection to said sensing element, means for effecting an operation of said connecting means, a timing device for rendering the operation effecting means of said connecting means effective only while the card is passing the sensing element and settable means arranged when set in one position to render effective an operation of said first named timing device and when set in another position to render effective an operation of said second timing device, means for completing a circuit to energize said magnet through its circuit connection, said sensing element, and said connecting means as the card advances to and before the card passes the sensing element, means rendered effective by said sensing element upon sensing a perforation as the card passes

said element for completing a second circuit to energize said magnet a second time through said circuit connection and said connecting means, an accumulating wheel, a driving element, said wheel and element being adapted for clutching engagement with one another, devices for coupling the two, devices operating upon said coupling devices to effect uncoupling, said coupling devices being responsive to said magnet when it receives said first impulse, means for causing said second named devices to be unresponsive to said first energization and means controlled by said coupling devices and said driving element for rendering said causing means ineffective so as to enable said second named devices to be responsive to a second energization of said magnet whereby the wheel and element are uncoupled.

7. The invention set forth in claim 5 in which a timing device is provided which is normally operative to render the operation effecting means of said connecting means effective only while the card is passing the sensing element and a second timing device is provided for rendering the operation effecting means of said connecting means effective as the card advances to and as it is passing by the sensing element, a further sensing element and means including said means for rendering the effecting means effective, controlled by said further sensing element in response to a special designation in the card for causing said second device to supersede the first named device in controlling the period of effective operation of said connecting means.

8. In a machine of the class described having an accumulator wheel which is to be advanced to any of a plurality of rotative positions to represent different digits, a continuously rotating driving wheel having a number of rotative positions with respect to a fixed point, including a succession of positions, one for each of the digits and a plurality of additional positions, said wheels being adapted for clutching engagement with each other, a spring-urged coupling device for effecting driving engagement between the wheels, a latch normally holding said coupling device out of operative position, and means for tripping said latch, including in combination, a shoe driven with said driving wheel and arranged to be engaged by the coupling device to prevent the effective operation of the latter when the latch is tripped during a predetermined one of said additional rotative positions of the driving wheel, said shoe being configured to hold the coupling device until the rotative position related to the digit 9 and to release the device at such time, and means driven with the driving wheel for disengaging the coupling device after all the digital positions have passed whereby the initial tripping of said latch at said additional rotative position will result in the advance of the accumulator wheel in accordance with the digit 9.

9. In a machine of the class described having an accumulator wheel which is to be advanced to any of a plurality of rotative positions to represent different digits, a continuously rotating driving wheel having a number of rotative po-

sitions with respect to a fixed point including a succession of positions, one for each of the digits and a plurality of additional positions, said wheels being adapted for clutching engagement with each other, a spring-urged coupling device for effecting driving engagement between the wheels, a latch normally holding said coupling device out of operative position, and means for tripping said latch, including in combination, 5 means coordinated with said driving wheel and effective when the latch is tripped during one of said additional rotative positions of the driving wheel for preventing clutch engagement at such position, said means serving to retard the coupling device and automatically release the same at the rotative position of the driving wheel related to one of the digits whereby clutching will be effected at said position and means for disengaging said coupling device at a position following said digital rotative position.

10. In a machine controlled by cards having a column of digit representing positions and an extra index point position, a pair of spaced sensing elements, means for advancing a record card to completely pass one element and then the other, with the column of digit representing index point positions and the extra index point position successively passing the elements including in combination, an accumulator magnet having a single winding, a normally incomplete circuit connection between said magnet and said second sensing element, a relay magnet for closing said connection, a second relay magnet for controlling the energization of the first-named 15 relay magnet, circuit connections including said second relay magnet, arranged to be completed and held under control of said first sensing element when a perforation is sensed thereby in said extra index point position, whereby said first-named relay magnet will close the connection between the second sensing element and said accumulator magnet and hold the connection closed until the card has passed the second sensing element, means for sending an impulse through said closed connections and said second sensing element before the card has reached the second sensing element and after it has passed the first sensing element, further means for sending a second impulse to the accumulator magnet through a perforation in any of the digital index point positions, the second sensing element and said closed connections, an accumulator wheel, a driving element, said wheel and element being adapted for clutching engagement 20 25 30 35 40 45 50 55 60 65 with one another, devices for coupling the two, devices operating upon said coupling devices to effect uncoupling, said coupling devices being responsive to said magnet when it receives said first impulse, means for causing said second named devices to be unresponsive to said first energization and means controlled by said coupling devices and said driving element for rendering said causing means ineffective so as to enable said second named devices to be responsive to a second energization of said magnet whereby the wheel and element are uncoupled.

EDWARD J. RABENDA.
